UNITED STATES PATENT OFFICE.

LAZARD KAHN, OF HAMILTON, OHIO, ASSIGNOR TO F. & L. KAHN & BBOS.,
OF SAME PLACE.

DESIGN FOR A GAS-BURNER.

SPECIFICATION forming part of Design No. 23,504, dated July 24, 1894.

Application filed June 2, 1894. Serial No. 513,323. Term of patent 7 years.

To all whom it may concern:

Be it known that I, LAZARD KAHN, a citizen of the United States, residing at Hamilton, Butler county, Ohio, have invented and produced a new and original Design for Gas-Burners, of which the following is a specification, reference being had to the accompanying drawing, showing the same in perspective.

The leading feature of my design consists of a burner-top formed of an annular series of upwardly presenting slitted bead-like protuberances, the body of the burner being circular in plan.

A, is the body of the burner, which is circular in plan. B, the center thereof: and C, 15 the annular series of slitted upwardly presenting bead-like protuberances upon the top of the body of the burner.

What I claim is—

The design for a gas burner substantially 20 as herein shown and described.

LAZARD KAHN.
